GAS-MIXER.

1,123,981.

Specification of Letters Patent.

Patented Jan. 5, 1915.

Application filed February 24, 1913. Serial No. 750,138.

To all whom it may concern:

Be it known that I, REINHOLD BERGFELD, a subject of the German Emperor, and resident of Berlin, Germany, have invented certain new and useful Improvements in Gas-Mixers, of which the following is a specification.

Various devices have been used hitherto for mixing within a gasometer the gas produced in the manufacture of illuminating gas. The necessity for mixing the gas arises from the variations in the specific gravity of the gas produced, the gas obtained at the beginning of an operation being of a different gravity from that obtained at the end of the operation, or when water gas is added to coal gas. The devices constructed heretofore do not however mix the gas satisfactorily unless gas is withdrawn from the holder or gasometer to the mains or place of consumption at the same time that the filling of the gasometer takes place.

In large gas works there are always several gasometers and often operating conditions will be such that after filling a gasometer its contents will be stored for several days before being delivered to the mains. Owing to the body of gas within such gasometer being at rest, the lighter gases will become separated from the heavier ones, the light-weight constituents collecting in the upper portion of the gasometer, while the heavy constituents sink to the bottom. If the contents of such a gasometer is discharged into the mains after this separation has taken place, the heavier gas will pass out first, and after a while a lighter gas will be fed to the place of consumption. Owing to the sensitiveness of modern gas burners, great drawbacks are experienced when the composition of the gas supplied from the mains is subject to variations.

According to my present invention, the difficulties pointed out above are overcome by mixing the gas in the gasometer with the aid of a blower, before feeding said gas to the mains. For this purpose I arrange between the inlet and the outlet of the gasometer, a blower of any suitable construction, with proper slides, dampers or valves, so that large quantities of gas may be withdrawn by said blower from the main chamber of the gasometer and immediately returned to said chamber, while at the same time the connections of the gasometer with

the gas generating plant and with the distributing mains are shut off.

In order that the agitation or whirling motion which the blower imparts to the gas may produce a thorough mixture it is important that the blower project the gas into the gasometer with a velocity sufficient to blow the gas upward as far as the top of the gasometer bell. When the blower is started, it will first withdraw the heavier gas which has accumulated at the bottom of the generator, so that the heavier portion of the gas will be forced back under the top of the gasometer, and after becoming distributed immediately below said top, the heavier gas will gradually sink within the gasometer, thus getting thoroughly mixed with the lighter gas. In order that the heavier gas may at first be withdrawn alone, the inlet of the suction pipe of the blower is arranged directly above the water level of the gasometer tank, while the delivery pipe of the blower terminates at a materially higher level than the suction pipe. With this arrangement, the gas jet discharged from the blower will strike and whirl only the upper layers of the gas contained in the gasometer, while the heavier gas at the lower portion of the gasometer will not be disturbed or carried along by the gas jet and will therefore flow even to the blower.

A specific embodiment of my invention is shown in the accompanying drawing, in which—

Figure 1 is a vertical section of a gasometer, showing in elevation a blower arranged to withdraw gas from the gasometer and to force it back into such gasometer; and Fig. 2 is a corresponding plan view, with the gasometer bell omitted.

The gasometer represented in the drawing consists of a tank 1 filled with water and a vertically-movable bell 2. Gas from the retorts or producing plant is fed to the gas space of the gasometer (interior of the bell 2) through the supply pipe 3, while the delivery pipe 4 is adapted to convey the gas from said space to the distributing mains. Suitable shut-off devices, such as the valves 5, 6 are provided to enable the interior of the gasometer to be disconnected from the producing plant and from the distributing mains, so that no additional gas from the producing plant may enter the

gasometer, nor any gas flow to the said mains. In a connection extending from the pipe 4 to the pipe 3 I provide a blower 7, or other impelling device, driven by power 5 in any suitable manner and having its connection with the pipes 3 and 4 controlled by suitable shut-off devices, such as the valves 8 and 9 respectively. The supply pipe 3 extends upwardly beyond the delivery pipe 4.

During the process of filling the gasometer, the valves 5 and 8 are in such a position as to allow gas to pass into the gasometer from the producing plant, while the valves 9 and 6 generally are in such a position as to permit the passage of gas from the gasometer to the distributing mains. If it be desired to mix the gas contained in the gasometer (as is desirable when such gas has not been drawn from for some time) the valves 5 and 6 are closed so that no fresh gas may reach the gasometer, and so that no gas may pass from the gasometer to the distributing mains. The valves 8 and 9 are 20 opened so as to connect the blower or impelling device 7 with the interior of the gasometer, and the said device is set in operation. This will at first withdraw the heavy gas contained in the lower portion of the bell 2, through the pipe 4 which is connected with the suction port of the impelling device 7, and the latter will force said gas back into the gasometer at a high velocity through the pipe 3 connected with the delivery port of 25 said device. The gas is discharged upward vertically and impinges against the lower surface of the top 10, thereupon spreading out laterally and gradually sinking to the lower portion of the gas space. After this operation has been continued for a short time, the entire body of gas confined in the gasometer will have been mixed 30 thoroughly so as to be of the proper uniform composition. The impelling device may then be stopped and the valves 8 and 9 closed. Upon opening the valve 6 the homogeneous gas may pass from the gasometer to the distributing mains.

It will be evident that the operation of 50 my invention is not dependent upon connecting the impelling device with the gas supply pipe 3 and with the gas delivery pipe 4, since the suction port and the delivery port of the impelling device may be connected with the gas space of the gasometer in other ways.

Various modifications may be made without departing from the nature of my invention as set forth in the appended claims.

60 I claim:

1. The combination, with a storage gasometer having a vertically-movable bell, of

an impelling device having a suction connection and a delivery connection both connected with the interior of said bell, whereby gas may be withdrawn from the interior of the movable bell and forced back into it for the purpose of mixing gases of different specific gravities. 65

2. The combination, with a storage gasometer having a vertically-movable bell, of an impelling device having a suction connection and a delivery connection both connected with the interior of said bell, the outlet end of the delivery connection being at a 75 higher level than the intake end of the suction connection. 70

3. The combination with a storage gasometer comprising a vertically movable bell and having a gas supply pipe and a gas delivery pipe both connected with the interior of said bell, of an impelling device having a suction connection with one of said pipes and a delivery connection with the other pipe, and shut-off devices controlling said 80 connections. 85

4. The combination, with an expansible receptacle for the storage of gas, of an impelling device having a suction connection and a delivery connection both connected 90 with the gas space of said receptacle, whereby gas may be withdrawn from the interior of said storage receptacle and forced back into it for the purpose of mixing gases of different specific gravities. 95

5. The combination, with an expansible receptacle for the storage of gas, of an impelling device having a suction connection and a delivery connection both connected with the gas space of said receptacle, the 100 outlet end of the delivery connection being at a higher level than the intake end of the suction connection within the said storage receptacle. 105

6. The combination, with an expansible receptacle for the storage of gas, a gas-delivery pipe extending from the gas-space of said receptacle to the outside of the receptacle, and a gas-supply pipe reaching into said gas-space, the end of the gas-supply pipe, within the receptacle, being at a 110 higher level than the intake end of the said delivery pipe, of an impelling device having a suction connection with said delivery pipe, and a delivery connection with said 115 supply pipe, and shut-off devices controlling said connections.

In testimony whereof, I have signed this specification in the presence of two subscribing witnesses.

REINHOLD BERGFELD.
